UNITED STATES PATENT OFFICE.

JACOB H. SPIRO, OF SAN FRANCISCO, CALIFORNIA.

DESIGN FOR A FINGER RING, BRACELET, OR SIMILAR ARTICLE OF MANUFACTURE.

Application filed May 31, 1922. Serial No. 2,485. Term of patent 3½ years.

To all whom it may concern:

Be it known that I, JACOB H. SPIRO, a citizen of the United States, residing at the city and county of San Francisco, State of California, have invented a new, original, and ornamental Design for Finger Ring, of which the following is a specification, reference being had to the accompanying drawing, forming part thereof.

The figure is a perspective view of a finger ring, bracelet or similar article of manufacture, showing my new design.

I claim:

The ornamental design for a finger ring, bracelet, or similar article of manufacture, as shown.

JACOB H. SPIRO.
